GRINDER FOR DRESSING SKINS

George M. Curtin, Gloversville, N. Y.

Application April 23, 1934, Serial No. 721,902

6 Claims. (Cl. 149—14)

This invention broadly relates to improvements in abrading machinery especially of the wide faced drum type adapted to dress fine tanned leather goods for glove making and the like purposes, and is more particularly concerned with certain protective devices that prevent the treated skins from unduly hugging or being inadvertently wrapped around an abrasive drum surface when operatively fed thereto.

10 The present instrumentalities are applicable to a dry skin grinder of the type disclosed in the Feix Patent No. 1,241,363 dated September 25, 1917. Such a machine may comprise a rapidly revolving abrasive drum together with a feed or 15 so-called presser roller that is reversely driven but at a relatively slower speed and made bodily shiftable toward or away from its cooperating abrasive drum. A marginal portion of a skin while longitudinally stretched in an unwrinkled 20 condition, is dexterously manipulated and gradually fed to this machine with its flesh side pressed snugly toward the abrading drum to remove its superfluous material. This operation results in a tanned leather product that is made uniformly 25 thin. After reaching the medial surface region, the treated skin is generally withdrawn by selectively releasing the presser roller and the skin then reversed from end to end to similarly process its remaining unfinished flesh surface. During 30 such procedure it is not an infrequent occurrence that the skin adheres unduly to the abrasive roller and is carried around therewith with a resulting abnormal wastage of material. Whenever the skin tends to grip in such fashion, 35 the operator manually reaches underneath the fast rotating abrasive drum to free the skin during its incipient seizing period, but such practice is attended with considerable hazard and has in the past, frequently led to serious maiming of 40 many experienced machine attendants.

The preventive measures herein embodied are centered in jet means which preferably eject a blast of air or other gaseous fluid tangentially against the abrasive drum in a direction counterwise to the path of the incoming treated product. The nozzle for my continuous air stream is so disposed that it will efficiently pick off and surround the drum hugging tendency displayed by machine treated skins, it having been found that 45 such unremitting safeguard effectively obviates the fabrication difficulties usually encountered when skin seizure occurs.

The abrasive drums are commonly built up from heavy cardboard discs or the like compressed 50 fibrous material and the cylindrical surface of

which has granules of abrasive glued thereto. After becoming dull or worn, such superimposed cutting surface is renewed in place, and in order to avoid clogging and otherwise defiling my safety appurtenances, the entire blower 60 equipment is preferably installed as a demountable machine accessory.

The object of my invention is to provide for a trustworthy yet extremely simple device of the character indicated and one that can readily 65 be applied to either existing or new grinders without requiring extensive changes in the structure thereof. Other objectives will appear in due course and all of which aspects will herein-after be set forth in detail.

Reference is had to the accompanying one sheet of drawings which is illustrative of a specific embodiment of my invention and in which drawing:

Fig. 1 schematically represents an elevational 75 cross-section of a grinder machine as taken transversely of the medial region of its abrasive roller and equipt with my improved devices; while Fig. 2 shows a horizontal view thereof as seen from line 2—2 of Fig. 1.

Referring first to the more conventional elements of a dry skin grinder assembly of the kind comprised in the cited Feix patent, these primarily include a belt driven abrasive drum 10 which relatively massive part may be mounted between 80 a pair of shaft journals such as 11 and rotated at a relatively high speed by the pulley 12. Said journals may respectively be carried upon complementary horizontal girders such as 13 that are spacedly supported by the upright framework 14. The lowermost portion of the framework may be equipt with a pair of crossbars such as 15 which respectively lie beneath said complementary girders. These crossbars may respectively be provided with an auxiliary journal such 95 as 16, having a cross-shaft 17 mounted therebetween.

Each upturned girder face may be fitted with a separate guideway 18; respectively resting thereon is a shiftable carriage element 19 and 100 across which is suspended a work table 36 for holding treated skins. Rack and pinion means such as 20 may serve to simultaneously actuate the respective carriage elements toward or radially away from the drum axis. To this end, a 105 pinion rockshaft may be extended laterally to have a toggle arm 21 attached thereto, said arm being linked to the pivoted foot treadle 22. If desired, an adjustable counterweight 24 or its equivalent may be used to load and thereby auto- 110

matically thrust the carriage elements 19 inwardly toward the abrasive drum surface in released treadle position. Mounted between said carriage elements is a sheathed presser or feed

5 roller 25 which may be brought closely contiguous to the abrasive drum surface but which roller may be withdrawn whenever the treadle is depressed. Said roller lightly presses the interposed skin against the abrading drum surface.

10 It is preferred to positively and continuously rotate the shiftable feed roller from the pulley 12 in a reverse direction from that of the drum. In the present instance, the drive is accomplished by the conventional chain and sprocket reduc-

15 tion gear 26 represented in Fig. 1. As indicated in dotted outline, supplementary guide rollers 27 and 28 may be installed to cooperate with the feed roller, but all such subordinate members merely assist in properly guiding the treated skin

20 29 between the drum 10 and the feed roller 25.

Referring now more specifically to the improvements applied to the described conventional grinder members, these may comprise a blast means of any suitable type or design but

25 preferably such that includes a casing 30 and a rotatable fan or blower 31 which may be in-

dependently driven in unison with the drum 10 by a direct connected motor 32. As an alterna-

30 tive, said blower may also be driven from the pulley 12 or the blast taken from any other conve-nient source, the intent being to insure an adequate blast supply during the period of grinder operation.

The blower casing 30 is shown provided with

35 a flange 33 which may be detachably secured to a contiguous portion of the framework 14. Said casing may further be equipped with a contracted delivery spout 34, preferably of the multiple nozzle type adapted to distribute the air blast length-

40 wise of the drum through a series of laterally dis-

posed jets 35A, 35B, etc.

Each such nozzle may be arranged underneath the rotating drum closely contiguous to but dis-

45 tant from the abrading surface so as to eject upwardly toward the rotating drum in tangen-

tially counterwise or other opposed relation to the surface movement, as shown. The use of a plurality of such jets is however, not essential

50 since a single nozzle blowing medially of the drum will normally suffice to start the leading extrem-

ity of a relatively small skin away from the abra-

55 sive surface, which in turn effectively extricates and overcomes the inherent tendency possessed by such treated skins to carry wholly around with the rotating drum.

It is thought the function of my tangentially directed air stream will now be apparent to those skilled in this art. When the treated skin is

60 descendingly fed through the described machine, its leading extremity usually drops away from the drum, but should its initial surface grip persist in dragging said skin into the operative region

65 of my air blast, such jet or jets serve in the capacity of a sentinel to promptly pick up and

cause the loosened leading skin end to pull away from the drum, whereupon its overhanging weight assists in drawing the remaining trailing skin portion free from the abrading surface.

Should it, after repeated dressing of the drum

70 surface, become necessary to renew the glued

abrasive material, it is preferred to bodily remove

the blast nozzle out of the way in order not to

clog or otherwise be foul the same with drippings.

As a further outstanding feature, all working

75 parts required to loosen the treated skin, are

herein deliberately kept spaced from the drum profile; that is to say, by the use of an air blast as projected to play upon the distant drum, none of the accessory elements need actually contact with its cutting surface nor be subjected to rapid abrasive action. In addition, my fluid spray when given sufficient penetration, tends to cleanse the abrasive drum surface from any abnormal accumulation of adhering foreign matter which might otherwise be deposited thereon be-cause of skin treatment.

It is to be understood that various other structural modifications may be resorted to in likewise carrying out my illustrative embodiments, all without departing from the spirit and scope of my invention heretofore described and more par-ticularly pointed out in the appended claims.

I claim:

1. In a machine for treating skins or the like, the combination of rotatably mounted drum means provided with an abrasive surface, feed roller means cooperating with said drum, drive means for rotating the drum surface, and blast means ejecting a gaseous fluid toward the drum in an opposed direction to the drum surface movement.

2. A skin processing machine comprising ro-tatably mounted drum means having a cylindri-cal abrasive surface, feed roller means cooper-ating with said drum, drive means for rotating the drum surface, and air blast means including a nozzle that is kept spaced from said drum sur-face and directs a jet of air thereagainst for skin pickoff purposes.

3. A skin processing machine comprising ro-tatably mounted drum means having a cylindri-cal abrasive surface, feed roller means co-operating with said drum, drive means for ro-tating the drum surface, and blast means includ-ing a plurality of nozzles that are distributed 110 lengthwise along said abrasive surface and re-spectively disposed to eject thereagainst.

4. A skin dressing machine comprising mount-ed drum means having an abrasive surface, co-operating feed roller means that are selectively 120 movable toward or away from said drum, drive means for positively rotating the drum and the roller at different speeds, blast means including a rotatable blower element together with a nozzle ejecting toward the abrasive drum surface, and means for rotating said blower in unison with the drum.

5. In a skin treating machine, the combination of drum means having an abrasive surface and which drum is rotatably supported by an under-lying framework, feed roller means cooperat-ing with said drum, drive means for rotating the drum, and blast means including a jet nozzle that is detachably upheld beneath said drum by said framework and which nozzle is directed to 130 eject upwardly against the abrasive drum sur-face.

6. In a machine for treating skins or the like, the combination of rotatably mounted drum means provided with a cylindrical abrasive sur-face, presser roller means cooperating with said 140 drum in contiguous perimetric relation to receive a skin therebetween, drive means for rotating the drum, and means ejecting a fluid stream toward the abrasive surface and which stream loosens a leading skin portion from said surface after hav-ing passed through the aforesaid perimetric re-gion.

GEORGE M. CURTIN.
